UNITED STATES PATENT OFFICE.

JOSEPH H. BARKER, OF CINCINNATI, OHIO.

DOOR-SPRING.

SPECIFICATION forming part of Letters Patent No. 224,377, dated February 10, 1880.

Application filed March 28, 1879.

To all whom it may concern:

Be it known that I, JOSEPH H. BARKER, of Cincinnati, in the county of Hamilton and State of Ohio, have invented certain new and useful Improvements in Door-Springs; and I do hereby declare the following to be a full, clear, and exact description of the same, which will enable others skilled in the art to which my invention relates to make and use it, reference being had to the accompanying drawings, forming part of this specification, in which—

Figure 1 is a perspective view of the spring complete. Fig. 2 is a similar view of the adjustable fastening detached from the spring. Fig. 3 is a longitudinal section of the adjustable fastening-head and bracket; and Fig. 4 is an elevation of the adjustable fastening applied to a mandrel, and showing the position of the wire preparatory to forming the spring.

Similar letters of reference denote the same parts in the several figures of the drawings.

This invention relates to door and gate springs, and has for its object to furnish such springs in which the angular tension-adjusting head, its supporting-bracket, and the coiled spring are inseparably and permanently connected together; and the invention consists in a bracket through which passes a cylindrical stud on the end of an angular head, the latter being provided above the bracket with two angular parallel lateral flanges, and the stud being provided, below the bracket, with an aperture, in which one end of the coiled spring is secured, a pin being arranged between the annular flanges which inclose the angular portion of the head, and bearing against the vertical portion of the bracket for holding the angular head in position, the construction being such, as more particularly hereinafter described, that the angular head, bracket, and coiled spring are inseparably and permanently connected together, and such parts form a homogeneous structure, rendering it impossible to accidentally separate the spring-head and bracket, and thereby the loss of either part is avoided.

In the accompanying drawings, A represents the spring, made in spiral form, of the proper-sized wire, secured at one end by a cleat, B, and at its other end to a head or stud, C,

which passes through a bracket, D, in which it turns freely. The cleat B is cast with a recess in its under side, which receives a loop formed at the end of the spring in such position that the retaining-screw, by which the cleat is secured to the door or jamb, passes also through the loop of the spring and secures both parts in place together.

The stud C is made with a lateral opening, e, to receive the opposite end of the spring and hold it in place. The outer end of the stud is an angular head, E, which, when the bracket is screwed to a door or jamb, is held in place and prevented from turning by a pin, p, which is passed between the two flanges g g, constituting part of the head, and engages one of the straight faces which form the periphery of the head between the flanges and the base of the bracket.

The spring having been applied to a door, if it should become necessary to increase or diminish its tension, a small wrench, which accompanies the attachment, is fitted over the supplemental head or boss h, by which the head can be turned in either direction, after removing the locking-pin to set the spring, as may be desired, when the locking-pin is again replaced. Thus a spring which has become weakened by long use can be easily adjusted to increase its force, or the force of the too powerful spring diminished. Thus the force of the spring may be adjusted to the resistance of the door to any desired degree of tension.

The essential difference in my invention from the ordinary door or gate spring consists in providing the head E with two parallel annular flanges, g, with the angular portion between them, and providing the stud C with an aperture, e, and after said stud is passed through the bracket, with the lower one of the flanges g resting on the bracket, securing the end of the coiled spring in said aperture, whereby the head, bracket, and spring are inseparably and permanently connected, and such parts form a homogeneous structure, rendering it impossible to accidentally separate the parts, and avoiding the loss of either.

The mode of forming and applying the spring to the adjustable head is shown in Fig. 4. The bracket D is held in a suitable clutch in the lathe, and the adjustable head held upon

one of the centers, with its other end engaging with a mandrel, I, as the other center. A suitable piece of wire being provided to form the spring, one end of it is inserted in the hole *c* 5 in the side of the stud C, and as the mandrel is then rotated the wire is spun into a spring of the proper length, first being bent at a right angle, where it emerges from the socket *c*, and spun closely upon the head C for at least 10 one entire revolution.

Having fully described my invention, what I claim, and desire to secure by Letters Patent, is—

The angular head E, constructed with the 15 two parallel annular flanges *g g*, and cylindrical stud C, having the aperture *c*, in combination with the right-angled bracket D, having

a circular aperture, through which the cylindrical stud passes, with the lower flange, *g*, resting on the bracket, and the coiled spring 20 A, having its end secured within the aperture *c* beneath the bracket, the whole constructed substantially as shown, whereby the angular head, bracket, and spring are permanently and inseparably connected together, and the 25 parallel flanges *g* serve to receive the locking-pin *p* between them and the face of the bracket, as set forth.

In testimony whereof I have hereunto set my hand this 17th day of March, 1879.

JOSEPH H. BARKER.
